Primary Examiner — Calvin E Vansant*Assistant Examiner* — Benjamin L. Gray(74) *Attorney, Agent, or Firm* — Merchant & Gould P.C.(57) **CLAIM**

An ornamental design for a lever as shown and described.

DESCRIPTION

FIG. 1 is a top perspective view of an exemplary lever according to a new design;

FIG. 2 is a left side view thereof;

FIG. 3 is a right side view thereof;

FIG. 4 is a front side view thereof;

FIG. 5 is a back side view thereof;

FIG. 6 is a top view thereof;

FIG. 7 is a bottom view thereof; and,

FIG. 8 is a bottom perspective view thereof.

The broken lines shown in the drawings illustrate portions of the lever that form no part of the claimed design.
